Harold D. Penney ATTORNEY

UNITED STATES PATENT OFFICE

PETER EUFINGER, OF FRANKFORT-ON-THE-MAIN, GERMANY, ASSIGNOR TO PETER LANCIER, OF MUNSTER, GERMANY

UNDERGROUND-CABLE-PULLING DEVICE

Application filed October 2, 1928, Serial No. 309,806, and in Germany March 23, 1928.

My present invention relates to an improvement in cable pulling devices such as are utilized for drawing cables through underground conduits and the like, and has for its main object the provision of means whereby the cables may be quickly and mechanically drawn through said conduits.

Another object of my invention is the provision of means whereby substantially intermittent or continuous drawing of the cable through the conduit is accomplished without loss of time and with greater economy than the present more laborious method of hauling by hand, or a motor driven

winch.

These and other capabilities will be readily understood as the description proceeds, and it is obvious that modifications may be made without departing from the spirit of the invention or the scope of the appended claims.

In the accompanying drawings:

Fig. 1 is a section of the characteristic manhole with portions of the cable conduits or ducts shown with my apparatus mounted in operative position.

Fig. 2 is a plan view of the apparatus as applied in position.

Fig. 3 is an enlarged elevational view of the apparatus with the support frame partly in section.

Figs. 4 and 5 show alternate means for drawing the cable either intermittently or continuously.

Fig. 6 is a view of the cable drawing device or snake.

As shown in Figs. 1 and 2 my device is readily applied in a conventional manhole 1 which is only fragmentarily shown, as it is well understood. Entering the manhole on opposite sides, in the usual fashion, there are located a plurality of sections 2 in which are located manhole ducts 3 through which cables are carried in such underground construction in the well known manner.

My particular apparatus consists of a frame, the details of which may be modified, but in the preferred form is as follows.

A pair of longitudinal channels 5 and 6, of common structural shape, are riveted to

gether, as at Figs. 1, 2 and 3, with their webs face to face, thereby forming, in substance, a pair of built-up I-beam strut members, the outer opposite ends of which are provided, as illustrated in Fig. 2, with fixed threaded studs 7. These studs have mounted thereon an expanding nut 8 which in turn bears against the outer surface of a series of thrust blocks 9, the footings of which rest against the side walls 10 of the manhole 1. It is obvious that these cross bar supports, by means of the thrust blocks 9, permit of adjustment and locking of the cable pulling frame work, to be later described, at any desired height of adjustment in relation to the cable duct 3 and are arranged to readily and quickly support the cable pulling mechanism in desired adjusted pulling position.

By referring to Fig. 2 it will be noted that there is mounted upon the cross frame supporting channel members 5 and 6 an upper transverse bearing frame 10^a which is affixed to the said members 5 and 6 in desired operative position. Supported upon the top of this transverse frame member 10^a are a pair of bearings 11-11 which operatively and rotatably mount in fixed position a chain sprocket wheel 12 which is driven by a chain 13, as in Fig. 1, from a pinion 14, which sprocket in turn is driven by any suitable means such as a hand crank or motor which may be mounted within the portable wheel truck 15, a portion of which is only shown in Fig. 1. Thus, movement of the sprocket 14 by any given power means causes the sprocket 12 to rotate upon its shaft 16 which is mounted within the bearings 11-11 and which shaft is rigidly affixed to the sprocket 12 whereby rotation of said sprocket causes said shaft to rotate. On both outer ends of the shaft 16 are mounted, as shown in Figs. 2 and 3, a pair of crank members 17-17, these being splined to the shaft 16 and are thus driven by the sprocket 12 upon rotation thereof. Attached to the outer ends of the cranks 17 are mounted a pair of connecting rods 18 whereby rotation of the cranks 17 will cause the said connecting rods 18 to reciprocate to operate the cable drawing mechanism, later to be described.

As a means for absorbing the shock of pulling of the cable in the form of device shown in Fig. 2, especially upon the reverse stroke thereof, there is provided a pair of extensible coil springs 19 mounted upon connecting links 20 which in turn are mounted upon the crank arms 17, and the opposite ends of said springs are attached to a cross bar 21 which is operatively held by a spring frame 22 which is rigidly attached to the supporting frame 10^a, as fully indicated in Figs. 2 and 3. Thus, upon the stroke opposite to the traction stroke unevenness of motion is balanced.

The transverse bearing frame 10^a is also provided on its opposite end, Figs. 1 to 3 inclusive, with a cable roller guide which is comprised of a pair of upstanding arms 23 upwardly and outwardly inclined, and there are mounted between them a plurality of cable rolls 24 which are mounted upon trunnions 25, these in turn being fixedly mounted upon the guide frames 23 so that when the cable is being withdrawn from the conduit and being laid upwardly and out of the man-hole and on to the cable drum 26, Fig. 1, the cable 27 is given an easy curve and guided upwardly in the direction to be readily taken up by the drum 26 as the slack of the cable is being thus removed.

The connecting rods 18 may be connected as in Fig. 5 to a cable draw or snake 28, this being in the usual form of a solid cylindrical collar 29 having trunnions 30 on opposite sides thereof whereby the opposite ends of the connecting rods 18 may be attached thereto so that rotation of the cranks 17 causes an oscillatory motion of the collar 29 at one end of which is affixed the said snake 28.

The snake 28 is in the form of a woven metal fabric or chain of cylindrical form which has thereon a diagonal weave as shown, whereby, when pushed upon it, expands and releases its grip upon the cable, but when drawn in the opposite direction toward the apparatus closes upon the cable and grips the same firmly and thus forms, in effect, a releasable cable gripping sleeve which automatically grips on the pulling or traction stroke, but automatically releases the same and slides back for a new grip when moved in reverse direction to the traction stroke. The snake is shown disconnected from the connecting rods in Fig. 6 as well as in Figs. 4 and 5.

In the action of the device as shown in Figs. 1, 2 and 5, the withdrawing of the cable from the ducts 3 is purely an intermittent one, as the snake engages and disengages in accordance with the rotary motion of the sprocket 12 and therefore releases intermittently and pulls intermittently in alternate sequence. It sometimes becomes desirable to move the cable in practically a continuous motion, to which end an alternate form of

connecting rod and snake connection is shown in Fig. 4 in which, as in Fig. 5, only the connecting rods 18 and their spindle mounting 16 are shown with the sprocket removed, and the crank arms 17 are mounted in opposite positions for opposite throw instead of being set for coincidental throw, as in Figs. 1, 2 and 5, thus obtaining a two-throw alternate crank motion rather than a two-throw single crank motion.

In the particular construction shown in Fig. 4, one connecting rod 18, which is shorter than the other connecting rod 18, is connected to a snake 28 on the opposite end of the snake sleeve 29 which is connected to a diagonal connecting rod 18' so that when the crank arm is in movement the snake is slid along and grips the cable 27, a portion of which cable is shown in this view.

The outer longer connecting rod 18 connects to a second snake 28 and has also a diagonal supplemental connected arm 18^a, the snake also being shown in operative engagement with the cable 27 with both cable snakes sufficiently spaced apart to permit of clearing movement of each other during their alternate oscillation.

It is obvious, from the foregoing description, that the structure shown in Fig. 4 is similar in every respect to the device shown in Fig. 5, with the exception that an alternate pick-up and pull cable, by the device shown in Fig. 5, is developed into a substantially continuous pick-up and pull, by the mechanism shown in Fig. 4.

It is to be noted that the pull carrying frame 10^a is transversely shiftable and lockable along its seat on the tops of the supporting channels 5-6 and this movement, together with the adjustability of the device against the side walls of the manhole 1, permits of an axial and universal alinement of the cable pulling device to any desired conduit duct from which it is desired to withdraw a cable.

Having thus described my invention, what I claim is:

1. In a cable puller of the class described an adjustable wall engaging frame, to bridge a manhole, a transversely shiftable bearing frame, lockably mounted thereon a shaft, revolvably supported by said bearing frame, a crank, secured to said shaft, and substantially horizontally disposed means, connected to said crank, for intermittently engaging and pulling a cable at said manhole.

2. In a cable puller of the class described an adjustable wall engaging frame, to bridge a manhole, a transversely shiftable bearing frame, lockably mounted thereon, a shaft, revolvably supported by said bearing frame, a crank, secured to said shaft, a substantially horizontally disposed means, connected to said crank, for intermittently engaging and

pulling a cable at said manhole, and means for directing the pulled cable upwardly.

3. In a cable puller of the class described an adjustable wall engaging frame, to bridge a manhole, a transversely shiftable bearing frame, lockably mounted thereon, a shaft, revolvably supported by said bearing frame, one or more cranks, secured to said shaft, a means, connected to said cranks, for intermittently engaging and pulling a cable at said manhole, and a resilient means for absorbing the shock of pulling the cable, connected to said cranks and said bearing frame.

4. In a cable puller of the class described an adjustable wall engaging frame, to bridge a manhole, a transversely shiftable bearing frame, lockably mounted thereon, a shaft, revolvably supported by said bearing frame, multiple cranks, secured to said shaft in opposite phases thereof, and means, connected to said cranks, for alternately pulling a cable at said manhole, thereby rendering the pulling effort substantially continuous.

5. In a cable puller of the class described an adjustable wall engaging frame, to bridge a manhole, a transversely shiftable bearing frame, lockably mounted thereon, a shaft, revolvably supported by said bearing frame, one or more cranks, secured to said shaft, a means, connected to said cranks, for intermittently engaging and pulling a cable at said manhole, and one or more springs, for absorbing the shock of pulling the cable, connected to said cranks and said bearing frame.

35 6. In a cable puller of the class described an adjustable wall engaging frame, to bridge a manhole, a transversely shiftable bearing frame, lockably mounted thereon, a shaft, revolvably supported by said bearing frame, a crank, secured to said shaft, a substantially horizontally disposed means, connected to said crank, for intermittently engaging and pulling a cable at said manhole, grooved rollers, for directing the pulled cable upwardly, and means for revolvably supporting said rollers, connected to said bearing frame.

50 7. In a cable puller of the class described an adjustable wall engaging frame, to bridge a manhole, a transversely shiftable bearing frame, lockably mounted thereon, a shaft, revolvably supported by said bearing frame, a crank, secured to said shaft, substantially horizontally disposed means, connected to said crank, for intermittently engaging and pulling a cable at said manhole, a source of power movably positioned over-head, and a means connected to said shaft, for transmitting motion thereto from said source.

60 8. In a cable puller of the class described an adjustable wall engaging frame, to bridge a manhole, a transversely shiftable bearing frame, lockably mounted thereon, a shaft, revolvably supported by said bearing frame, a crank, secured to said shaft, substantially horizontally disposed means, connected to

said crank, for intermittently engaging and pulling a cable at said manhole, a source of power, movably positioned overhead, a sprocket wheel at said source, another sprocket wheel on said shaft, and a chain in mesh with said wheels, for transmitting motion to said shaft from said source.

70 9. In a cable puller of the class described an adjustable wall engaging frame, to bridge a manhole at a desired level thereof, a transversely shiftable bearing frame, lockably mounted thereon, said bearing frame being transversely shiftable and lockable along its seat on said wall engaging frame, thereby providing with the adjustability of said wall engaging frame a means for universal alignment, a shaft, revolvably supported by said bearing frame, a crank, secured to said shaft, and means, connected to said crank, for intermittently engaging and pulling a cable at said manhole.

75 10. In a cable puller of the class described a cable gripping woven sleeve, which has thereon a diagonal weave, whereby, when pushed upon, it expands and releases its grip upon the cable, and, when drawn in the opposite direction, it closes upon the cable and grips the same firmly, and a means for alternately moving said sleeve in opposite directions on said cable, thereby alternately pulling the cable and releasing the same and moving said sleeve with relation to said cable.

80 Signed at Frankfort-on-the-Main, Germany, in the county of Hessen-Nassau and State of Prussia this 21st day of September 100
